THERMIT AMMUNITION

Maurice E. Barker, Washington, D. C., assignor
to the United States of America as represented
by the Secretary of War

Application February 12, 1942, Serial No. 430,609

9 Claims. (Cl. 102—90)

(Granted under the act of March 3, 1883, as
amended April 30, 1928, 370 O. G. 757)

1

The invention described herein may be manufactured and used by or for the Government for governmental purposes, without the payment of any royalty thereon.

This invention relates to incendiary munitions such as projectiles in the form of artillery shells, aerial bombs and similar types of explosive shells equipped for scattering instrumentalities of conflagration.

A broad aim of the present invention is to provide a device of this character that will effectively expel ignited fluid and scatter it, together with ignited or inflammable pellets in all directions to result in conflagrations giving off intense heat and dispersed over a considerable radius.

In its broadest aspect, the invention consists in the provisions of a casing in which is retained an inflammable fluid and incendiary pellets suspended in the fluid. An explosive or bursting charge is confined within the casing for fragmentizing the latter, igniting the fluid and pellets, and forcibly expelling and diffusing the burning fluid and pellets. In turn the pellets, by reason of the characteristic features thereof as contemplated by this invention, will, during trajectory flight, explode or fragmentize to scatter the burning particles thereof over a wide area. Thus the device possesses a degree of extended and effective destructiveness not reached by prior available incendiaries.

The device is of simple and safe construction, lending itself to mass production, and to use as either an artillery projectile, an aerial bomb or shell, or to the "firing" thereof in situ.

The above and other features of the invention combining to present an incendiary munition capable of attaining the stated and apparent objects will be better understood and appreciated from a study of the following description made in connection with the accompanying drawings, wherein:

Figure 1 is a fragmentary view, partly in elevation and partly in section, of an incendiary device, and illustrating an application of the invention;

Figure 2 is a longitudinal sectional view of one form of pellet forming part of the invention; and

Figure 3 is a view similar to Figure 2 and illustrating an alternate form of pellet.

Referring to the drawing more in detail, 5 indicates a casing which may be made of steel, iron or other suitable material. The shape of casing 5 will be determined by the manner of intended use of the finished device, or in other words, whether the finished article is to be used as an artillery projectile, an aerial bomb or shell, or is to be

"fired" in situ. In the present instance the casing is illustrated as being of the usual shell configuration.

The casing 5 is divided into an explosive-containing chamber 6 and a fluid and pellet-containing chamber 7 through the medium of a partition 8. In the present instance the partition 8, which is relatively thin and of the same material, preferably, as casing 5, is illustrated as being screw threadedly secured in position.

Confined within chamber 6 is an explosive or bursting charge 9, while confined within chamber 7 is an inflammable fluid 10 and pellets 11. Pellets 11 are suspended in the fluid as shown in Figure 1.

The explosive or bursting charge 9 may be of any desired material or type. Also since the means for detonating the bursting charge may be varied at will and as the manner of using the device may dictate, no such means is herein illustrated or described.

Inflammable fluid 10 is preferably an oil which may be either a very viscous liquid or may be solid, the essential characteristic of the same being that it be highly inflammable to the end that the stated and desired objects of the invention be attained.

Essentially each of the several pellets 11, as illustrated, embodies an outer casing of combustible material, preferably nitrocellulose, and a filling of incendiary composition, as for example and by way of preference, of the class of Thermit.

In Figure 2 the enveloping nitrocellulose casing of the form of pellet therein shown is indicated by the reference numeral 13 and the Thermit filling by the reference character 14.

In Figure 3 the enveloping nitrocellulose casing of the alternate form of pellet therein illustrated is indicated by the numeral 113 and forms an exterior sealing jacket for a shell or receptacle like member 15 of magnesium metal or material of a kind that burns with an intense heat. The Thermit filling 114 is encased in the member 15 which is open at one end as shown.

The pellets are of bullet-like shape and each has confined within one end thereof a wad 16 in the form of a disc and composed of black powder for setting fire to the highly inflammable filler 14 or 114 as the case may be. When, as illustrated in Figure 3, the member 15 or its equivalent is employed the wad 16 serves as a plug or closure for the open end of said member.

All of the pellets 11 in chamber 7 may be of the form shown in Figure 2, or of the form shown in Figure 3, or the pellet-contents of the chamber

may include both forms of pellets, as may be found most advantageous.

It will be seen that when casing 5 bursts under the action of its explosive charge 9, such explosion will likewise disrupt the partition disc 8, and the parts of the casing, the fluid 10, and the pellets 11 will be thrown and scattered in all directions. Incidental to the explosion the fluid 10 is subjected to the heat from the explosive material and ignites. In turn the casings 13 and/or 113, as the case may be, of the pellets 11 are ignited and consequently during trajectory flight the combustible material or Thermit filling is set on fire. Hence in the case of the pellets of Figure 2 they are scattered over an extensive area as whole burning masses. In the case of the pellets of Figure 3 the powder 16 is subjected to the heat of the burning envelope 113 which in turn results in the ignition of the Thermit filling and the bursting of the magnesium shells 15 which burn in the presence of the oxygen of the air. As a consequence each pellet of the type just referred to is reduced to a multiplicity of particles that burn with an intense heat, setting fire to practically any object with which any one of such particles may come into contact.

Thus with this device a flaming mass of oil and Thermit is spread or dispersed over a considerable area, and the desired results will be obtained whether the munition be in the form of a projectile fired from a gun, or in the form of an aerial bomb or shell to be dropped from an aeroplane, or in the form of an explosive fired in situ.

It is believed that the foregoing sets forth the invention in such detail as will enable others to fully appreciate the advantages thereof and to adapt the munition to various applications within the meaning and range of equivalency of the following claims, the precise details of construction as herein set forth being by way of illustration and not by way of restriction.

What is claimed as the invention is:

1. In a device of the character described, a casing having therein a chamber for an explosive charge and a second partitioned chamber for incendiary instrumentalities, an explosive charge in the first chamber, and incendiary instrumentalities in the second chamber and in the form of dispersible combustible fluid and pellets suspended in the fluid, said pellets embodying an inflammable casing and a filling of Thermite.

2. In an explosive shell, a dispersible charge of combustible fluid and a plurality of pellets in suspension in the fluid; each of said pellets embodying an inflammable magnesium casing and a filling of incendiary composition.

3. In an explosive shell, a dispersible charge of combustible fluid and a plurality of pellets in suspension in the fluid; each of said pellets embodying a shell-like container of combustible material, an incendiary composition confined within said container, and a casing of inflammable material enveloping the container.

5 4. In an explosive shell, a dispersible charge of combustible fluid and a plurality of pellets, each of which embodies a casing and a filling including a charge of incendiary composition of the class of Thermit and a wad of combustible powder.

10 5. In an explosive shell, a dispersible charge of combustible fluid and a plurality of pellets, each of which consists of a container formed of magnesium metal, Thermit in the container, a wad of combustible powder closing the open end of the container, and an enveloping outer casing of inflammable material.

20 6. A dispersible incendiary charge consisting of a multiplicity of pellets suspended in an inflammable fluid; each of the pellets embodying an outer casing of nitrocellulose and a filling of incendiary composition.

25 7. A dispersible incendiary charge consisting of a plurality of pellets suspended in an inflammable fluid; each of the pellets embodying a shell-like container of magnesium metal, a filling of incendiary composition in the container, and an enveloping outer casing of nitrocellulose material.

30 8. An incendiary pellet composed of an outer casing of nitrocellulose material, and a filling consisting of a charge of Thermit and a wad of black powder.

35 9. An incendiary pellet composed of an outer casing of nitrocellulose material, and a filling consisting of a charge of Thermit and a wad of black powder encased in a shell of magnesium metal.

40 MAURICE E. BARKER.
